UNITED STATES PATENT OFFICE.

MILTON KELLOGG, OF CHICAGO, ILLINOIS, ASSIGNOR TO UNDERWOOD TYPEWRITER COMPANY, OF NEW YORK, N. Y., A CORPORATION OF NEW JERSEY.

SILENT-KEY MECHANISM.

SPECIFICATION forming part of Letters Patent No. 745,356, dated December 1, 1903.

Application filed August 29, 1903. Serial No. 171,172. (No model.)

To all whom it may concern:

Be it known that I, MILTON KELLOGG, a citizen of the United States, and a resident of Chicago, county of Cook, and State of Illinois, 5 have invented certain new and useful Improvements in Silent-Key Mechanisms, of which the following is a specification.

My invention relates to silent-key mechanisms for type-writers and like machines, and 10 has for its object to provide a simple mechanism capable of ready attachment to existing type-writing machines.

The invention will be fully described hereinafter and the features of novelty pointed 15 out in the accompanying claims.

Reference is to be had to the accompanying drawings, in which—

Figure 1 is a sectional elevation from front to rear of a type-writer embodying my invention. Fig. 2 is a plan with parts in section 20 on line 2 2 of Fig. 3, and Fig. 3 is a sectional elevation on line 3 3 of Fig. 2.

A indicates the frame of the type-writer; B, the carriage with the platen C; D, one of 25 the key-levers, which in this case belongs to one of the silent keys, said lever being fulcrumed at D' and being returned to its normal position by a spring E. The connection of the key-lever D with the impression mechanism is effected in any suitable manner—as, 30 for instance, by means of an elbow-lever F, fulcrumed at F' and having two pin-and-slot connections—one, F², with the key-lever D, and the other, F³, with the type-bar G, fulcrumed at G' on the segment H.

D² is the silent key, and I is the space-key, connected with levers J, carried by a rock-shaft J', from which also extends an arm J², 35 engaging the rock-arm K, fulcrumed at K', which is connected with the escapement mechanism (not shown) in any suitable manner. It will be understood that the ordinary step-by-step feed movement of the carriage occurs 40 during the upward or return movement of the space-bar I.

A so-called "silent key" is one the operation of which effects an impression without causing the carriage to be fed. In order to prevent the carriage being fed when the key D² is de-

pressed, I provide an arm L, arranged to be 50 engaged and depressed by the key-lever D, as indicated in Fig. 1, the said arm being secured upon a rock-shaft M, as by means of a set-screw M'. This arm is provided at its lower portion with a cam-surface L', adapted 55 to engage a rod N, secured to the levers J at a distance from their fulcrum. In Figs. 2 and 3 I have shown three arms L, corresponding to three silent keys. It will be understood that the set-screw connection enables 60 these arms to be adjusted along the rock-shaft M to any desired position.

The number of silent keys may of course vary. If there was only one silent key located at the right, it would not be necessary 65 to employ a rod N extending from one lever J to the other, but it would be sufficient to provide the projecting portion N', which is located exteriorly of the right-hand lever J, as shown in Fig. 3. The rod N will herein- 70 after be termed an "operating" projection connected with the space-bar. When the silent key D² is depressed, the arm L will be rocked with its cam-surface L', so as to depress the levers J and the space-bar I, and 75 these parts will be locked in their lower position, so that when the key-lever D² returns to its normal upper position the space-bar will not be allowed to release the escapement for the feed of the carriage. Therefore when 80 the next character is printed such character will come in the same space as the accent or other mark printed by the depression of the silent key.

It obviously is necessary that the escapement should be released as soon as one of the ordinary type-keys is depressed. For this purpose I have secured to the rock-shaft M a releasing member which consists of a bar O, adapted to be engaged by the key-levers of 90 the ordinary type-bars and secured to said rock-shaft by arms O'. This bar is rocked upward when the key-lever D of a silent key is depressed. Thereupon when one of the ordinary keys is depressed its key-lever will 95 engage the bar O and will swing the same downward in such a manner as to remove the cam-surface L' from the operating projection

N. The space-bar I will thus be released, and the customary feed movement of the carriage will take place when the ordinary type-key returns to its normal position. Obviously 5 the key-levers D of the silent keys should be so arranged as to have no action on the bar O. This may be done in any suitable manner—for instance, as shown in Fig. 2, by providing notches O² in the bar O at those places where a key-lever D of a silent key occurs. Thus whenever a silent key is depressed the space-bar will be locked in that position which corresponds to the stationary position of the carriage, and whenever thereupon one of the 15 ordinary type-keys is depressed the space-bar will be released, so as to allow the carriage to be fed in the customary manner.

The arm L (shown at the right in Fig. 2) is located beyond the end of the bar O, and of course no notch O² is required for this arm L.

Various modifications may be made without departing from the nature of my invention.

I claim—

25 1. The combination with the silent key and its key-lever, of a space-bar provided with an operating projection, a locking-arm adapted to be operated by the depression of the silent key and arranged to engage said operating 30 projection to lock the space-bar, and means for releasing the space-bar.

2. The combination with the silent key and its key-lever, of a space-bar, an operating projection connected with said space-bar, locking mechanism adapted to be operated by the 35 depression of the silent key and arranged to

engage said operating projection, and means for releasing the space-bar.

3. The combination with the silent key, the space-bar provided with an operating projection, a rock-shaft provided with an arm adapted to be moved by the depression of the silent key and arranged to engage said operating projection to lock the space-bar, and means for releasing the space-bar. 40 45

4. The combination with the silent key, the space-bar provided with an operating projection, a rock-shaft provided with an arm adapted to be moved by the depression of the silent key and arranged to engage said operating projection to lock the space-bar, and a releasing member connected with said rock-shaft and adapted to be engaged by the ordinary key-levers. 50

5. The combination with the silent key, of a space-key, a lever carrying the same, a device operated by the depression of the silent key for locking said lever directly, and a device for releasing the space-key lever, operated by the depression of any one of the ordinary type-keys. 55 60

6. The combination with a silent key, of a space-key, a lever carrying the same, and a device operated by the depression of the silent key for locking said lever directly. 65

In testimony whereof I have signed my name to this specification in the presence of two subscribing witnesses.

MILTON KELLOGG.
